UNITED STATES PATENT OFFICE.

PHILIP M. BORJA, OF NEW YORK, N. Y.

PIANO.

1,294,866.

Specification of Letters Patent.

Patented Feb. 18, 1919.

Application filed May 31, 1917. Serial No. 171,910.

To all whom it may concern:

Be it known that I, PHILIP M. BORJA, a citizen of Mexico, (first United States citizenship papers taken out,) and a resident of the city of New York, borough of Manhattan, in the county and State of New York, have invented a new and Improved Piano, of which the following is a full, clear, and exact description.

10 This invention relates to pianos and has for an object the provision of an improved construction wherein the keys will be on the same plane or substantially the same plane as the upper surface of the body of the 15 piano.

Another object in view is to provide an improved arrangement of music desk which may be folded so as to cover the keys and to complete the covering of the top of the 20 mechanism of the piano.

A still further object of the invention is to provide a folding top for a piano which may be opened to any desired extent from a small opening to a complete hinging of 25 the top pieces along the sides.

In the accompanying drawings:—

Figure 1 is a top plan view of a piano disclosing an embodiment of the invention.

Fig. 2 is a side view of the structure shown 30 in Fig. 1, the lid being shown in its fully open position.

Fig. 3 is a front view of the piano with the top boards or sections in a partially raised position.

35 Fig. 4 is a detail fragmentary sectional view through Fig. 1 on line 4—4.

Fig. 5 is an enlarged detail fragmentary sectional view showing the arrangement of hinge for the top members or boards.

40 Referring to the accompanying drawings by numerals, 1 indicates suitable supporting legs which may be of any kind, the same being connected with a case 2 of any preferred kind, said case supporting in the usual manner the members 3 which include the pedals 4 for operating certain parts of the mechanism as the piano is being played.

45 Arranged at the front of the piano is a keyboard 5 positioned slightly above the top of the piano, whereby the operator's fingers can be seen across the piano from any direction. In forming the top or lid of the piano the same is divided into sections 6 and 7, as shown in Fig. 1, section 7 having an 50 auxiliary section 8 hinged to the main part of the section, as shown in Fig. 2, whereby

the same may be folded forwardly if desired. These sections are hinged to the case 2 by suitable hinges 21 and 22 so as to be raised as shown in Fig. 3 and held supported 60 by the props 10 and 10' or be moved completely over so as to occupy the position shown in full lines in Fig. 2 and dotted lines in Fig. 3. When in the folded position as shown in Fig. 1 the lids are supported by 65 resting against the edges of the case and against the transverse bar 11.

As indicated in Figs. 1 and 4 the lid of the piano is notched or cut-away at 7' in order that the easel body 16 may lie flush 70 with the top of the lid when the parts are folded as shown in figures either 1 or 4.

With this arrangement of lid or lids a specially hinged easel must be provided for the music, and also a cover must be provided 75 for the keys. As shown in Fig. 4 the cover 12 is hinged at 14 to the upright 15, and is provided with an upstanding portion 13 which acts as a music desk when the parts are in the dotted position shown in Fig. 2. 80 In order to hold the cover 12 in the dotted position shown in Fig. 2 an easel body 16 is provided, hinged at 17 to the board 18, said easel body being capable of being raised to the position shown in Fig. 2 and held in such 85 position by a brace 19 pivotally connected to the board 20. In order to accommodate this brace when the easel body 16 is in a lowered or folded position, as shown in Figs. 1 and 4, the notch 7' accommodates the easel 90 body 16 and a groove 16' in board 20 accommodates the brace 19 whereby the upper surface of the easel body will lie flush with the lid 7. The board 20 may be permanently or otherwise positioned in the notch 7' and is of 95 a thickness to fill the notch 7' after the easel body has been folded. The board 20 is designed to keep the top of the piano closed when the easel body 16 is raised in order not to interfere with the usual musical effect. 100

When the lid sections 6 and 7 are raised as shown in Fig. 3, the same are supported by suitable props or braces 10 and 10' and the easel body 16 is also raised and held in position by the brace 19. The cover 12 is 105 then opened and moved to the dotted position shown in Fig. 2, whereupon the piano is in proper condition for playing. The cover 12 when in this position acts as a support for the music, but when no music is being used the parts are folded back to the 110 position shown in Fig. 4, whereupon the op-

operator's fingers will be seen from any direction above the piano.

To shut the piano from an open position as shown in Figs. 2 and 3 the cover 12 is moved from the keys and the easel body 16 and associated parts are folded downwardly to the position shown in Fig. 4, after which the lid sections 6 and 7 are folded to a closed position. By this construction and arrangement not only are the keys of the piano in substantially the same horizontal plane as the upper edge of the piano so as to expose the fingers of the operator, but the piano may be maintained closed during the playing or may be opened partially or entirely, according to the size of the room and other surrounding conditions.

What I claim is:

1. A piano including a case, a keyboard positioned slightly above the plane of the upper edge of the case, and a covering member for said keyboard.

2. A piano including a case, a keyboard arranged slightly above the plane of the upper edge of said case, a foldable covering member for the keyboard, said foldable covering member being formed with an up-standing portion acting as a music desk, and

an easel body hinged to said case near said covering member.

3. A piano including a case, a keyboard and a lid for covering said case divided into sections, the respective sections of said lid being hinged to said case in such a manner as to be movable through about 270°.

4. A piano including a case, a lid having a notch, a keyboard arranged slightly above the plane of the upper edge of the case, an easel body of less thickness than said lid and normally positioned in said notch, and a covering board arranged beneath said easel body in said notch for maintaining closed said notch when the easel body is moved to an operative position.

5. A piano including a case, a lid for said case having a notch, said lid being divided into sections, a board normally filling the lower part of said notch, an easel body resting on said board when in a folded position and filling the remaining part of said notch, said easel body acting as part of the music support when unfolded and elevated, and a covering member for the keyboard of the piano resting when open against said easel body for completing the music support.

PHILIP M. BORJA.
